DRAWING FRAME

Ralph C. Berker, Hoxsie, R. I.

Application April 22, 1947, Serial No. 743,023

11 Claims. (Cl. 19—129)

1

This invention relates to drawing frames and particularly to a novel method and apparatus for effective high speed drawing of wool and like fibers preparatory to the spinning process.

In processing wool and like materials as received from the Nobel combs preparatory to the spinning process, the sliver is passed through a series of gill drawing frames so as to provide the necessary blending, drawing and doubling of the slivers. This manner of processing wool to produce a sliver or slubbing requires the packaging of each sliver as delivered from the gill frame so as to be transferred to the next gill frame of the set. Further, the conventional gill drawing frame has opposite sets of faller bars or combs which are traversed through the wool fibers by so-called gill screws. Such an apparatus is operated at a relatively low speed.

One of the objects of this invention is to improve generally upon the conventional practice of processing wool sliver preparatory to the spinning process.

Another object of the invention is the provision of a drawing apparatus wherein a single pass of wool slivers therethrough shall produce a sliver comparable to a like product produced by the separate action thereon of a series of gill frames.

Another object of the invention is the provision of a gill drawing apparatus for drawing, doubling and imparting a twist to wool sliver.

Another object of this invention is to improve generally on gill drawing frames.

Another object of this invention is to provide a gill drawing frame having a larger number of fallers in a space comparable to a like space in the conventional gill drawing frame.

Another object of this invention is to provide a gill drawing frame so constructed as to be operable at a much higher speed than heretofore.

Another object of this invention is to provide a gill drawing head so constructed as to eliminate the usual gill screws, faller cams and conductors.

A more specific object of this invention is to simplify the construction of gill drawing heads.

Another object of this invention is to provide a gill drawing head wherein the fallers will be positively carried from one path of movement to the other.

Another object of this invention is the provision of a gill head so constructed wherein the force for moving or traversing the fallers along their path of travel will be transmitted through one faller to another and each be advanced thereby to the end of its path of travel.

Another object of this invention is the provision of a gill head construction wherein the fallers will be advanced in their path of travel by a pushing action.

Another object of this invention is the provision of a gill head construction wherein the

2

fallers will be advanced along their path of travel in intermittent steps.

Another object of this invention is the provision of a gill drawing head which can be manufactured at a comparatively low cost of production and which will be durable and satisfactory in use.

With these and other objects in view, the invention consists of certain novel features of construction as will be more fully described and particularly pointed out in the appended claims.

In the accompanying drawings:

Fig. 1 is a plan view illustrating diagrammatically a drafting apparatus embodying my invention;

Fig. 2 is a front view of a gill head of the drafting apparatus shown in Fig. 1;

Fig. 3 is a sectional view taken substantially along line 3—3 of Fig. 2 showing the faller transferring mechanism;

Fig. 4 is a sectional view taken substantially along line 4—4 of Fig. 2;

Fig. 5 is a sectional view taken substantially along line 5—5 of Fig. 4;

Fig. 6 is a sectional view taken substantially along line 6—6 of Fig. 5;

Fig. 7 is a sectional view taken substantially along line 7—7 of Fig. 3;

Fig. 8 is a sectional view taken substantially along line 8—8 of Fig. 3;

Fig. 9 is a perspective view of one of the fallers made according to the invention;

Fig. 10 is a perspective view of a transfer member employed for moving the fallers from one path of travel to the other;

Fig. 11 is an elevational view of a fragmentary portion of a modified construction of faller and means for transferring the same from one path of movement to the other;

Fig. 12 is a sectional view of the faller shown in Fig. 11 and taken along line 12—12 of Fig. 11;

Fig. 13 is an end view of a further modification of a construction for transferring a faller from one path of movement to the other;

Fig. 14 is an elevational view of a fragmental portion of the structure shown in Fig. 13;

Fig. 15 is an elevational view of a fragmental portion of a construction for transferring a faller from one path of travel to the other wherein the end portion of a faller may be strengthened;

Fig. 16 is a diagrammatic view of the gearing between the power shaft and the vertical shaft of each gill head.

In carrying out my novel process, the wool sliver, as received from the Nobel combs in forms of tops, is passed through a plurality of gill heads which are positioned in side-by-side relation. The slivers, after passing through these gill heads, are guided to be doubled or formed into a single sliver. This single sliver is guided to a plurality of spaced sets of drawing rollers. The sliver is carried from one set of drawing rollers

to the other by carrier rolls which are positioned between each set of drawing rollers as is usual in apparatus of this type. The sliver, after being acted upon by the plurality of sets of drawing rollers, is received in another gill head and a set of drawing rollers to be further combed and drawn. From the last drawing operation, the sliver is received by a twisting and take-up mechanism which imparts a twist to the sliver and packages the same in the form of a slubbing.

This new method of processing wool as received from the Nobel combs to produce a slubbing eliminates the heretofore necessary packaging and transferring of sliver from one gill drawing frame to the other.

Referring to the drawings for a more detailed description of the invention, 10 designates generally an apparatus in which the above described process may be conveniently carried out. The apparatus 10, shown more or less diagrammatically in Fig. 1 of the drawings, comprises a plurality of gill heads 11 which are positioned in side-by-side relation and are constructed in a manner to be hereinafter described. Each gill head will receive a single or a doubled sliver as the case may be depending upon the desired blend and weight of slubbing desired. The combs of each gill head will act upon the slivers in a manner usual in apparatus of this character, but at a much higher rate of traverse of the combs through the wool fibers because of the particular construction of gill head.

In front of these gill heads, a transfer plate or guide 12 is positioned for receiving the slivers from the drawing rollers 11' of the gill heads. This transfer plate is provided with a plurality of openings 13, 14 and 15 through which the sliver passes to be guided thereby and formed into a single sliver. In the present instance, the openings 13, 14 are positioned in the plate so as to be opposite the end gill heads 16 and 17. The sliver 18 from the gill head 16 is threaded through the opening 13, while the sliver 19 from the gill head 17 is threaded through opening 14. These two slivers 18 and 19 are then led beneath the plate and pass upwardly through the opening 15 to be merged with the sliver 20 from the centrally positioned gill head of the set. A trumpet or like guide 21 is mounted in a line with the opening 15 at a position to receive and compact the now single sliver 22.

The sliver 22 is received from the guide 21 and acted upon by a plurality of sets of drawing rollers 23. These are mounted in spaced relation and in line with each other in tandem fashion in front of the guide 21. Each set of drawing rollers may be of a usual construction and may consist of two lower fluted rollers 24 and 25 and an upper smooth roller 26. Between each set of drawing rollers, there is positioned a pair of driven rollers 27 for supporting and moving the sliver from one set of drawing rollers to the other. These may also be of any approved design. A single gill head 28 is positioned in front of the sets of drawing rollers 23 to receive the sliver 22 after acted upon by the drawing rollers 23. The gill head 28 is of a construction similar to the gill heads 11 and is provided with a usual set of drawing rollers 29 which cooperate with the combs of the gill head to provide a second combing and further drawing of the sliver 22. The sliver as delivered from the drawing rollers 29 is received by a packaging and twisting mechanism which may be of a usual construction and includes a take-up spool 30 and a flier

31. By means of the flier 31, a twist is imparted to the sliver to form the same into a slubbing.

I have shown an apparatus having three gill heads 11 positioned side by side and three sets 5 of drawing rollers interposed between the heads 11 and 28. However, the number of gill heads and sets of drawing rollers may be increased or decreased in accordance with the character of the materials acted upon or the quality of work 10 desired, for example, in some instances two gill heads in spaced tandem relation may be provided with a plurality of sets of drawing rollers interposed between the gill heads, such as by omitting the heads 16 and 17. In illustrating the apparatus 15 diagrammatically, I have omitted showing any supporting means or framework for mounting the parts shown or means for rotating the sets of drawing rollers. Since such means form no part of the present invention, it is not necessary to show the same for a clear understanding 20 of the invention.

Each gill head (see Fig. 2) comprises opposite spaced supports or bearing members 32 and 33. The bearing members 32 and 33 are similarly 25 constructed and are rigidly attached at their lower portion to a support 34 forming part of the framework of the drawing apparatus. The bearing members 32 and 33 are further tied to each other at their upper end portion by means of 30 lugs or ears 35 which protrude upwardly from each bearing member with the ears on one bearing member positioned opposite to an ear on the other bearing member. The ears are each provided with an opening 36, and a tie rod 37 extends between opposite ears. The end portion of 35 each rod is threaded and reduced in diameter so as to extend through an opening 36 with the shoulder 37' formed thereon engaging the surface about the opening 36. A split washer 38 and a nut 39 secure the end portion of the tie rod in place to the ear.

Between these bearing members there extends an upper and a lower set of fallers designated generally 40 and 41, respectively. The two sets 45 of fallers are moved in separate parallel paths which extend from one end portion of the bearing member to the other and return along separate parallel paths. Thus, each set of fallers travels in one path in one direction and return in the opposite direction in another path. As is well known in the art, during the working stroke of the fallers, the pins on one set of fallers intersect the pins on the other set as the same is traversed through the fibers of the sliver. Accordingly, one end portion of the upper set of fallers is supported 50 and slidably mounted on bars or saddles 42 and 43 which are mounted in the bearing member 32 in parallel relation and extend lengthwise of the bearing members. The opposite end portions of 55 these fallers are similarly supported in similarly disposed saddles 44 and 45 in the bearing member 33. The lower set of fallers 41 are similarly supported and slidably mounted on saddles 46 and 47 on the bearing member 32 and saddles 48 and 49 on the bearing member 33. The upper set of 60 fallers is moved or traversed along the saddles 43 and 45 from one end portion of the bearing members to the other end thereof and return along the saddles 42 and 44. The lower set of fallers are similarly moved in one direction along 65 the saddles 46 and 48 and return along the saddles 47 and 49. The saddles 43 and 45 provide the path along which the fallers of the upper set are moved during the working stroke thereof, 70 while the saddles 46 and 48 provide a similar ad-

acent parallel path for the fallers of the lower set during the working stroke thereof. The fallers of the upper set are returned along the path formed by the saddles 42 and 44 and the fallers of the lower set are returned along the path formed by the saddles 47 and 49. Each faller 50 (see Fig. 5) is provided with spurs or pins 51. The pins 51 on one set of fallers are arranged to be spaced in staggered relation with respect to the pins 51 on the other set of fallers. The end portion of each faller is provided with an opening 52.

The fallers of the upper set are mounted so that the pins 51 thereon depend therefrom, and the lower fallers are mounted so that the pins 51 thereon extend upwardly therefrom. The path of movement of the sliver through the gill head is located between the saddles 43 and 45 and the saddles 46 and 48. The pins 51 are of a length so that those on one set of fallers will intersect the pins on the other set of fallers as traversed longitudinally through the fibers being drawn and combed through the gill head.

There are a plurality of fallers in each set and these are positioned to be in contact with each other along their horizontal paths of travel. The fallers are moved lengthwise of the bearing members by a mechanism designated generally 53 (see Fig. 4). There is one of such mechanisms 53 positioned at one end of each path of travel in each of the bearing members 32 and 33. Each mechanism 53 is substantially of a similar construction and arrangement and only one will be described in detail. The mechanism comprises an elongated member or pin 54 having an enlarged head 55. The pin 54 slidably extends through an opening 56 in an end wall 57 of the bearing member at a location to be in line with an end portion of the fallers. The pin 54 is movable into and out of engagement with the adjacent end faller of the group. The amount of movement of the pin 54 is such as to move the fallers at each work stroke of the pin a distance substantially equal to the thickness of a faller.

The pin 54 is cam actuated to be moved toward and into engagement with the fallers. Accordingly, a lever 58 is pivotally mounted to a support 59 as at 60. One arm 61 of the lever extends into engagement with the head 55, and the other arm 62 extends into engagement with a short rod or pin 63. This pin 63 slidably extends through an opening 64 in the wall 57. The inner end extremity 65 of the pin 63 engages with the surface of a cam 66 and is moved thereby to rock the lever 58 to move the pin 54 into engagement with the fallers and move the same as previously described. The pin 54 is moved in the opposite direction or away from the fallers by means of a compression spring 67. The spring encircles the body of the pin with one end thereof abutting against the head 55 and the other end thereof resting on the bottom of a cavity 68 provided by enlarging the opening 56. The timing of the apparatus in the present arrangement is such that the pin 54 will be reciprocated twice for each revolution of the cam.

In order to transfer the fallers from one path of travel to the other, transfer mechanisms designated generally 69 and 70 are provided (see Figs. 3 and 5). One of these mechanisms is provided at the end of one path of travel of each set of fallers at each end portion of the fallers. In other words, there is a transfer mechanism 69 in each bearing member 32 and 33 positioned at the end of the working stroke of the fallers of

the upper set to transfer the fallers to their return path of movement. There is a mechanism 70 in each bearing member 32 and 33 positioned at the end of the return stroke of the fallers to transfer the same into the path of the working stroke of the upper set. The lower set of fallers is similarly provided with similar mechanisms.

Since each set of fallers is similarly mounted at its end portion in members 32 and 33 and the mechanisms for operating each set of fallers is also of a similar construction and arrangement, only the mechanism for operating one end portion of a set of fallers will be described in detail.

The transfer mechanism 69 comprises a member 71 having a body portion of a disk formation provided with a central opening 72 (see Figs. 5 and 10). Two pins or studs 73 extend from one side of the body diametrically opposite to each other. This member 71 is mounted for rotation in a recess 74 with the studs 73 thereon extending in the end portion of the path of travel of the fallers. The transfer mechanism 70 (see Fig. 3) is positioned opposite to and at the other end portion of the bearing members and also comprises a member 75 having a body portion of a disk formation and which is provided with two studs 76 diametrically spaced from each other a distance equal to the spacing of the studs 73 on member 71. The member 75 has a hub 77 which is journaled for rotation in anti-friction member 78 mounted in end wall 79. The hub 77 has a reduced end portion 80 for a purpose to be hereinafter described.

The bearing members 32 and 33 are essentially of a similar construction and arrangement and each comprises an upper and lower section 81 and 82, respectively (see Fig. 3). The upper section 81 normally rests against the flat top face 83 of the lower section 82. The upper section 81 may be arranged to be moved away from the lower section in any suitable manner and preferably a hinged joint 84 is provided with an axis substantially coincident with the parting line between the two sections 81 and 82. The hinge 85 between the two sections may consist of ears 85 and 86 which project rearwardly from the outer side of the sections and each is formed with hubs 87 and 88, respectively, through which extends a pivot pin or stud 88 held in place in any suitable manner.

Each section 81 and 82 is of substantially similar construction and formed so as to provide recesses 89 and 90 in the upper section and recesses 91 and 92 in the lower section. In these recesses, the end portions of the fallers may be moved (see Fig. 2). These recesses provide shelves or ledges 93, 94, 95 and 96 forming mountings for the saddles which are bolted thereto by screws 97.

In the upper section 81 (see Fig. 3), a shaft 100 is mounted for rotation. This shaft 100 has a reduced end portion 101 which extends through the opening 12 in member 71 and is journaled in anti-friction bearing 102 mounted in the end wall 103. Member 71 is fastened to the reduced portion 101 by key 104. The other end of the shaft 100 has a reduced end portion 101' which extends through the hub 77 of member 75 and is spaced therefrom so as to permit relative rotation therebetween. The reduced portion 101' is journaled in the end wall 105 by means of anti-friction bearing 106 mounted therein. A shaft 107 is similarly mounted in the lower section 82 and has a member 71 fastened thereto as above described.

On the reduced hub portion 80 of the transfer device 70, a gear 108 is received and fastened thereto by a key or spline 109. The reduced portion 80' of the hub 77 of the member 75 in the lower section 82 is extended to provide a bearing for a bevel gear 110 which is keyed to rotate therewith. The beveled gear 110 is provided with a hub having a reduced portion 111 which receives a gear wheel 116 which is fastened thereto in any suitable manner such as by a spline or key 117. Motion is transferred from the beveled gear 110 to the gear 108 by means of idler gears 118 and 119, these two idlers being in engagement with each other and with the gears 108 and 116.

Motion for rotating bevel gear 110 and shafts 100 and 107 is derived from any suitable source which may be transmitted through a horizontal shaft 120 on which are mounted beveled gears 121 for each gill head. Each bearing member 32 and 33 is provided with a vertical shaft 122 which is properly mounted, such as by an upright support 123 secured to the base or frame 34 of the machine. The lower end of shaft 122 is provided with a gear 127 which engages with gear 121. The upper part of the support 123 is provided with a truss bearing 124. Mounted on this vertical shaft at the upper end portion thereof so as to rest on the bearing 124 is a beveled gear 125. This gear is fastened to the shaft 122 such as by a spline 126. It will be apparent that the rotation of the shaft 122 will, through gears 125 and 110, transmit motion to the gear 116 fastened to the hub of the gear 110 and through gears 118 and 119 to the gear 108 and thereby to mechanism 70 in the upper section 81. Motion is transmitted to mechanism 70 in the lower section through gear 110.

The rotation of mechanism 69 is had through a beveled gear 128 which engages with the gear 125. This gear 128 is mounted on the shaft 107 and is secured thereto in any suitable manner such as by a spline 129. This gear 128 is also provided with a hub portion 130 to which is splined a gear 131. To shaft 101' a gear 132 is 45 splined so as to rotate therewith. Motion is transferred from the gear 121 to gear 132 by means of idler gears 133 and 134 (see Fig. 8).

In transferring a faller from an upper to a lower path of travel, the faller is moved in a space 50 at the ends of the path of travel which is designated generally 135 (see Fig. 6). In order to support the fallers which are moved to register with the space 135 prior to being transferred to the lower path, a spherical member 136 is 55 mounted in any opening 137 which has a restricted opening 138 through which the members 136 partly protrude into the space 135 to be engaged by the lower edge of the end of the faller. A compression spring 139 biases the sphere 60 toward the space 135 and a screw 140 maintains the spring in adjusted position. When the faller is moved by the transfer member, the member 136 will yield under the force applied to the faller.

In Fig. 11, I have shown a modification of faller and transfer mechanism which comprises an arm 141 which is rotatably mounted and from which a single stud 142 projects. This stud engages with an opening 143 provided on the end portion of the faller. The arm 141 is also provided with a hub portion 144 which provides a support for holding the end faller in position prior to its being transferred to another path of travel.

As the group of fallers is advanced in its path 75

of travel, the first faller of the group will be advanced to a position in the path of travel of the stud 142 with the curved extremity 143' thereof riding on the hub 144. As the arm 141 rotates to engage the stud 142 with the opening 143, the hub 144 will be rotating out of engagement with the curved surface 143'. The relation between the stud and hub is such that when the stud is fully within the opening 143 the hub will have been moved out of supporting engagement with the surface 143' to permit transferring of the faller to another path of travel.

In Figs. 13 and 14, I have shown a further modification in which instance the faller is provided with a stud 147 extending from the end extremity thereof and the transfer mechanism is provided with openings 148. The operations of the several modifications are all somewhat similar and constitute Geneva motions whereby the fallers are moved from one path of travel to the other at substantially right angles thereto.

In Fig. 15, I have shown a similar construction but modified to the extent that the faller is provided with two openings 145 and 146.

In this modified construction, the faller will be moved from an upper to a lower path of travel by the stud on the arm of the transfer member engaging with the upper opening 145 in a manner similar to that above described for the construction shown in Figs. 11 and 12. In moving a faller from a lower to an upper path of travel the stud on the lower transfer member will engage with the lower opening 146. The hub of arm 141 will be omitted and the faller being transferred will be supported in the mounting thereof. In this construction, a stronger faller end portion may be constructed.

The operation of the several parts of the gill head has been given in connection with the detailed description thereof, and a brief general description of the operation of the gill head as a whole will suffice in order to clearly understand its mode of operation. With the movable parts of the head set into action in proper timed relation, the pin 54 (see Fig. 4) will be actuated by means of the cam surface 66. This cam surface, in the present instance, is formed integral with the transfer members 69 and 70 on the side thereof opposite to that from which the studs extend. The movement of this pin 54 will engage the faller previously positioned in the space adjacent thereto and move the same a distance substantially equal to its thickness. This movement of the faller will be transmitted through all of the fallers in this path of travel and advance the further faller of this group of fallers into the space in which a stud of a transfer member extends. The stud on the transfer member in its rotation will engage the walls of the opening 52 in the end portions of the faller and move the faller to a position opposite its other path of travel so as to be acted upon by a pin 54 of another mechanism 53 to be along such path and also move the fallers ahead of it in this path to feed the most advanced faller thereof to be similarly acted upon by the transfer mechanism positioned at the end of this latter path.

I claim:

1. A gill-drawing apparatus comprising oppositely spaced bearing members, a plurality of fallers extending generally horizontally between said bearing members with the end portions of said fallers slidably mounted in said bearing members and movable lengthwise thereof in op-

posite paths of travel, means at the end of each path of travel engaging said fallers for moving the same along said paths, and second means having a portion thereof inter-locking with said fallers for transferring the same from one path of travel to the other.

2. A gill-drawing apparatus comprising oppositely spaced bearing members, a plurality of fallers extending generally horizontally between said bearing members with their end portions slidably mounted in said bearing members and movable in opposite paths of travel, means at the end of each path of travel for engaging said fallers for moving the same in one direction along said paths, a transfer member at the end of each path of travel having a portion thereof inter-locking with said fallers for transferring said fallers from one path of travel to the other and means for actuating said transfer member.

3. A gill-drawing apparatus comprising oppositely spaced bearing members, a plurality of fallers extending between said bearing members with their end portions slidably mounted in said bearing members and provided with an opening, said fallers being movable lengthwise of the bearing members in opposite directions, a pin positioned at one end in each path of travel and movable into and out of engagement with said fallers for moving the same along said paths of travel, a transfer member rotatably mounted at the opposite end of each path of travel and having a pin thereon for engaging with the opening in the fallers for moving and transferring the fallers from one path of movement to the other.

4. A gill-drawing apparatus comprising oppositely spaced bearing members, a plurality of fallers extending generally horizontally between said bearing members and movable in opposite paths of travel and having openings in the end thereof, means at the end of each path of travel for engaging said fallers for moving the same in one direction along said paths, a transfer member at the end of each path of travel having a pin receivable in said openings for engaging and transferring said fallers from one path of travel to the other and means for actuating said transfer member.

5. A gill-drawing apparatus comprising oppositely spaced bearing members, a plurality of fallers extending generally horizontally between said bearing members and movable in opposite paths of travel and having openings in the end thereof, means at the end of each path of travel for engaging said fallers for moving the same in one direction along said paths, a transfer member at the end of each path of travel having spaced pins receivable in said openings for engaging and transferring said fallers from one path of travel to the other and means for actuating said transfer member.

6. A gill-drawing apparatus comprising oppositely spaced bearing members, a plurality of fallers extending generally horizontally between said bearing members and movable in opposite paths of travel and having an opening in the ends thereof, means at the end of each path of travel for engaging said fallers for moving the same in one direction along said paths, a transfer member at the end of each path of travel for engaging and transferring said fallers from one path of travel to the other and means for actuating said transfer members, said transfer member and the apertured end portion of said fallers constituting a Geneva mechanism.

7. A gill-drawing apparatus comprising op-

ositely spaced bearing members, a plurality of fallers extending between said members and in contact with each other and with the end portions thereof slidably mounted in said bearing members for movement lengthwise thereof and means including a pin slidably mounted for reciprocal linear movement for engaging and applying a pushing action to the end faller in a path of travel thereof to be transmitted through one faller to another for advancing said fallers in said path of travel.

8. A gill-drawing apparatus comprising oppositely spaced bearing members, a plurality of fallers extending between said members and in contact with each other and with their end portions slidably mounted in said bearing members, a pin slidably mounted for reciprocal linear movement and engaging the end faller for moving said fallers lengthwise of said bearing members, and cam means for actuating said pin.

9. A gill-drawing apparatus comprising oppositely spaced bearing members, a plurality of fallers extending between said bearing members and with their end portions slidably mounted in said bearing members and movable lengthwise thereof in opposite paths of travel, means including a pin slidably mounted for reciprocal linear movement for engaging and moving said fallers in one path of travel and second means for transferring said fallers to the other path of travel.

10. A gill-drawing apparatus comprising oppositely spaced bearing members, a plurality of fallers extending between said bearing members and with their end portions slidably mounted in said bearing members and movable lengthwise thereof in opposite paths of travel, means including a pin slidably mounted for reciprocal linear movement for engaging the end faller at one end of a path of travel of said fallers for moving the same in said path of travel, and means positioned at the opposite end of said path of travel for transferring said fallers to the other path of travel.

11. A gill-drawing apparatus comprising oppositely spaced bearing members, a plurality of fallers extending between said bearing members with their end portions slidably mounted in said bearing members, a pin slidably mounted for reciprocal linear movement movable into and out of engagement with said fallers for moving the same lengthwise of said bearing members, a pivoted lever for engaging said pin and moving the same into engagement with a faller and cam means for actuating said lever.

RALPH C. BERKER.
